(No Model.)

E. WOODWARD.

HAY CARRIER.

No. 301,036.

Patented June 24, 1884.

UNITED STATES PATENT OFFICE.

EDWIN WOODWARD, OF STRYKER, OHIO.

HAY-CARRIER.

SPECIFICATION forming part of Letters Patent No. 301,036, dated June 24, 1884.

Application filed April 29, 1884. (No model.)

To all whom it may concern:

Be it known that I, EDWIN WOODWARD, of Stryker, in the county of Williams and State of Ohio, have invented certain new and useful Improvements in Hay-Carriers, of which the following is a full, clear, and exact description.

Reference is to be had to the accompanying drawings, forming part of this specification, in which similar letters of reference indicate corresponding parts in all the figures.

Figure 1 is a side elevation of one of my improved carriers, part being broken away, and showing the operating parts in position to receive the bail of the fork-carrying pulley. Fig. 2 is the same view as Fig. 1, but showing the operating parts in position to support the fork-carrying pulley and its attachments. Fig. 3 is a sectional end elevation of the same, taken through the broken line $x\ x$, Fig. 2. Fig. 4 is a sectional plan view of the same, taken through the line $y\ y$, Fig. 1. Fig. 5 is an elevation of the double catch, the track being shown in section through the line $z\ z$, Fig. 2.

The object of this invention is to facilitate the operation of transferring hay from the wagon to the hay-mow, and secure certainty in the action of the operating mechanism of hay-carriers.

The invention consists in the combination, with the two plates forming the frame of the carrier, of two hook-plates adapted to be tripped by the bail of the fork-pulley and to engage with each other and the catch. The first hook-plate is made with two hook-arms, to adapt it to engage with the second hook-plate to support the loaded fork and hold the second hook-plate in gear with its catch. The second hook-plate is made with two hook-arms and a curved trip-arm, having a shoulder at its inner end, to adapt the said plate to engage with and be tripped by the first hook-plate and to engage with the catch, as will be hereinafter fully described.

A represents the track, which is designed to be supported from the frame-timbers of a barn by angle-bolts or other suitable means.

The carrier-frame is formed of two plates or frames, B, which are connected by bolts, and the upper parts of which are at such a distance apart as to receive between them the

track A. To the upper corners of each of the plates B are pivoted rollers C, to roll along the upper side of the track A. To the rear lower corners of the plates B is attached the end of the traction-rope D, which passes over a pulley, E, pivoted to and between the lower forward corners of the said plates B. From the pulley E the rope D is led over guide-pulleys in the ordinary manner to the place where the horse is to be attached. Upon the rope D, between its stationary rear end and the pulley E, is placed a pulley, F, with the block G of which is connected the hay-fork in the ordinary manner.

The guide-pulleys for the rope D and the hay-fork are not shown in the drawings.

To the block G of the pulley F are rigidly attached the ends of the bail H, which projects upward to trip the operating parts of the carrier, hereinafter described.

To and between the forward lower parts of the plates B, a little in the rear of the pulley E, is pivoted a two-armed plate, I, the arms of which project about at right angles with each other. The outer end of the upper arm of the plate I is rounded, and has a hook, 1, formed upon its outer side edge. The lower arm of the two-armed plate I has a hook, 2, formed upon the outer end of its outer side edge.

To and between the rear lower parts of the plates B, and at a little higher level than the pivot of the plate I, is pivoted a three-armed plate, J, upon the outer end of the outer side edge of the lower arm of which is formed a hook, 3.

Upon the outer end of the outer side edge of the outer arm of the three-armed plate J is formed a hook, 4. The third arm of the three-armed plate J is convexed upon its outer side and concaved upon its inner side, as shown in Figs. 1 and 2, and has a shoulder, 5, upon the outer part of its inner end.

To the lower side of the center of the track A is attached a catch, K, which is made double to adapt it to be used without change when the carrier is upon either arm of the said track. The catch K is made with a dovetailed recess in the center of its lower side, with the lower sides of its end parts slightly concaved, and with square outer ends. The catch K has upward projecting perforated lugs, 6, upon

the opposite sides of its center to overlap the sides of the track A, and receive the bolt by which the said catch is secured to the said track, as shown in Fig. 5. With this construction, when the carrier is over the hay-wagon and the hook-plates I J are in the position shown in Fig. 1, when the pulley F, carrying the loaded fork, rises to the carrier, the bail H strikes the upper arm of the hook-plate I and raises it, and also raises the inner arm of the hook-plate J, withdrawing the hook 4 from the catch K and allowing the carrier to be drawn forward by the traction-rope D, the hook-plates I J being in the position shown in Fig. 2. When the carrier is drawn back for another load and reaches the catch K, the end shoulder, 5, of the hook-plate J strikes the end of the said catch K, which turns the said hook-plate and withdraws the hook 3 from the hook 2 of the hook-plate I, releasing the bail H and allowing the unloaded fork to descend for another load. This movement raises the hook 4 into contact with the catch K and lowers the hook 1 into contact with the hook 3, so that the weight of the arm of the plate I will hold the hook 4 of the plate J in contact with the catch K, and thus prevent the carrier from being moved out of place accidentally.

Having thus described my invention, what I claim as new, and desire to secure by Letters Patent, is—

1. In a hay-carrier, the combination of the pivoted plate I, formed with the hooks 1 2 at its opposite ends, with the pivoted plate J, formed with a curved trip-arm having shoulder 5 and hook-arm 4 on its upper end, and with the depending arm having a hook, 3, for engaging the hooks 1 2 of plate I, all arranged substantially as and for the purpose set forth. 35

2. The combination, with the frame-plates 40 B, slotted on their lower edges, as shown, and the block and bail H, of the pivoted plate I, having hooks 1 2, and the plate J; pivoted above and on the opposite side of the slot from the plate I, and formed with a trip-arm 45 projecting across the slots in the path of the bail H, shoulder 5, hook-arm 4, projecting out of the frame-plates, as shown, and the depending hook-arm 3, all constructed and arranged substantially as set forth. 50

3. The catch K, formed with a dovetailed recess in the center of its lower side, and with the lower sides of its end parts concaved, as shown, and the upward-projecting perforated lugs 6 on its opposite sides to overlap the sides 55 of the track, substantially as set forth.

EDWIN WOODWARD.
